(57) **CLAIM**

I claim the ornamental design for a behind the ear sound processor, as shown and described.

DESCRIPTION

FIG. 1 is a rear perspective view of a behind the ear sound processor constructed in accordance with one embodiment of the present invention;

FIG. 2 is a rear elevation view thereof;

FIG. 3 is a front elevation view thereof;

FIG. 4 is a top side elevation view thereof;

FIG. 5 is a right side elevation view thereof;

FIG. 6 is a bottom side elevation view thereof;

FIG. 7 is an exploded rear perspective view thereof;

FIG. 8 is an exploded rear elevation view thereof;

FIG. 9 is an exploded front elevation view thereof;

FIG. 10 is an exploded top side elevation view thereof;

FIG. 11 is an exploded right side elevation view thereof; and,

FIG. 12 is an exploded bottom side elevation view thereof.

The broken lines in the drawings depict unclaimed environmental subject matter and form no part of the claimed design.
